Primary Examiner — Karen S Acker*(74) Attorney, Agent, or Firm* — Knobbe, Martens, Olson & Bear, LLP(57) **CLAIM**

The ornamental design for a furniture seating, as shown and described.

DESCRIPTION

FIG. 1 is a top, front, and right-side perspective view of a furniture seating;

FIG. 2 is a bottom, rear, and left-side perspective view thereof;

FIG. 3 is a front elevational view thereof;

FIG. 4 is a rear elevational view thereof;

FIG. 5 is a left-side elevational view thereof;

FIG. 6 is a right-side elevational thereof;

FIG. 7 is a top plan view thereof; and,

FIG. 8 is a bottom plan view thereof.

The broken lines in the figures depict portions of the furniture seating that form no part of the claimed design. The dot dash dot broken lines in the drawings depict the boundaries of the claim and form no part thereof.

1 Claim, 8 Drawing Sheets
